L. W. GRASNICK

SUSPENDERS

Filed Sept. 28, 1921

INVENTOR
Louis W. Grasnick

BY C.P. Goepel.

ATTORNEY

UNITED STATES PATENT OFFICE.

LOUIS W. GRASNICK, OF NEW YORK, N. Y.

SUSPENDERS.

Application filed September 28, 1921. Serial No. 503,888.

To all whom it may concern:

Be it known that I, LOUIS W. GRASNICK, a citizen of the United States, and a resident of the borough of Bronx, city, county, and State of New York, have invented certain new and useful Improvements in Suspenders, of which the following is a specification.

This invention relates in general to garment supporters of the class known as suspenders, and has for its primary object to produce a device of a character stated, which is simple in construction, effective in operation and durable in use.

More particularly the invention has for its object to provide suspenders which will have all the capabilities of rubber elastic webbing without having the tendency of rubber webbing to wear out and become ineffective. To that end the invention consists 20 in providing suspenders with compression springs which although sensitive in action are durable and efficient when in use.

With these and other objects in view hereinafter stated the invention consists in the construction and arrangement of parts hereinafter more fully described and illustrated in the accompanying drawings in which like numerals designate corresponding parts throughout the several views.

30 As illustrated in the drawings:

Figure 1 is a perspective of a suspender embodying the invention.

Figure 2 is a perspective of the connecting member shown in Figure 1 detached from the body of the suspender and a perspective of a supporting strap partly broken away.

Figure 3 is a side elevation of a compression spring casing and a longitudinal section of a covering for said casing, together with 40 a section of a connecting strap attached to the upper end thereof and of a supporting strap and loop connection connected with the lower end thereof.

Figure 4 is a side elevation of the parts shown in Figure 3.

Figure 5 is a vertical longitudinal section of a compression spring casing shown in Figure 3 enlarged and detached.

Figure 6 is a vertical longitudinal section 50 taken on the line 6—6 of Figure 5.

Figure 7 is a transverse section taken on the line 7—7 of Figure 5.

Figure 8 is a similar section taken on the line 8—8 of Figure 5 and

Figure 9 is a similar section taken on the line 9—9 of Figure 5.

As shown in the drawings the suspender is provided with the usual crossed body members 1 of inelastic webbing and with the usual garment supporting straps 2 provided with button holes 3 and if desired with clasping sockets 4.

Between the body members and the garment supporting straps, connecting members are provided including a strap 5 with clasps 6 adapted to engage a corresponding stud 7 formed on or connected with a leather covering 8 containing the coil compression spring casing 9. The strap 5 at its fixed end may be attached to or connected with the upper portion of the leather covering 8. The opposite walls of the casing 9 are preferably indented to form within the casing parallel chambers within which are contained coil compression springs 10 supporting on their upper ends, socket heads 11 within which is arranged the knotted ends 12 of a cord 13 which extends downwardly through one of said springs and outwardly from said casing forming a loop 14 and back up through the other spring so that a downward pull on the loop 14 will cause the springs 10 to be compressed, and when said pressure is released from said loop the springs will expand. The lower ends of the springs 10 are supported upon a plate 15, the margins of said plate being in turn supported upon the inturned edges 16 of the casing 9. For convenience of construction I prefer to make the plate 15 separate from the body of the casing 9 in most cases, although such an arrangement is not an essential feature of the invention.

The connecting members attached to the back ends of the body portions are of the same general construction as those attached to the front ends without the adjustable strap 5.

The manner of attaching the connecting straps to the body portions is not essential although for most purposes I prefer to make the connections with the front ends of the body portion by means of a link 17 and to apply the connecting member at the back ends of the body of the device directly to 100 said member.

The supporting straps 2 may be linked with the connecting member in any suitable

manner, such as by means of a coupling 18 connected with the loop 14 and on its free end provided with a stud adapted to engage a clasp 19 attached to the free end of said coupling.

When in use the device is well adapted to support a garment with an even tension around the entire waist band and to yield comfortably to any position assumed by the 10 body of the wearer. The metal coil springs moreover give a quick and positive response to any pull exerted upon any part of the suspender when in use and all tendency of the flexible or yielding part of the suspender 15 to wear out in advance of the body of the suspender is avoided.

Now particularly it will be noted that the 20 socket heads 11 are of tulip or tubular cup shape having as shown in Figure 6, a bell shape flange 23, against which one end 33 of the spring 10 abuts and having an opening through which the cord 13 passes. The spring 10 surrounds the cup shaped socket at its exterior and as the socket is pulled 25 down more and more convolutions of the spring surround the body portion 20 of the socket 11 because the downward pull of the sockets compress the spring. The knotted end 12 of the cord 13 seats within the hollow or tubular socket. The socket may be pulled 30 down almost to the plate 15, depending on the amount of space necessary for the compressed spring. It will be also noted, that the casing 9 has the wall 30 having the ends 35 31 as shown in Fig. 4. These ends 31 do not impede the passage of the spring 31 or the passage of the socket. The lower end of the casing 9 has a flare 35, and along the openings of the plate 15 for passage of the cords 40 13, the plate is upset or rounded off as at 36, so that the cords have a smooth bearing surface 36. The lower terminal end 25 of the spring 10 fits against the bottom plate 15 as indicated in Figure 6.

45 What I claim as new and desire to secure by Letters Patent is:

1. In a suspender, a connecting member comprising a casing having adjoining tubular chambers, coil springs arranged in said 50 chambers, socket members carried by the upper portions of said springs, and a flexible connection having its end portions extending into opposite chambers and with its intermediate part extending without the

chambers, the terminal ends of said flexible 55 connection being secured to said socket members, the cords passing flexibly and loosely through the central portions of the coil springs and being relatively small in diameter as compared with the diameter of said 60 springs.

2. In a suspender, a connecting member comprising a casing having its opposed walls indented centrally to provide a pair of tubular adjoining chambers, said chambers having their base portions flared outwardly and provided with inturned ends, a bottom seated upon said inturned ends and having openings therein coaxial with said chambers, coil 65 springs in said chambers seated upon said bottom, socket members carried by the upper ends of said coil springs and a cord having its end portions extending through the openings in the bottom, up centrally through said coil springs and secured to said socket 75 members, with the intermediate portion of the cord extending upon the exterior of the casing.

3. In a suspender, a connecting member comprising a casing provided with parallel 80 chambers therein, coil springs mounted in said chambers, a supporting cord having its free ends connected with the upper ends of said springs and its middle portion projecting through the lower end of said casing to 85 form a loop, and a cover for said casing having a strap connected therewith and provided with a plurality of sockets adapted to engage a stud connected with the cover for said casing.

4. In a suspender, a connecting member comprising a casing, a coil spring within the casing, a supporting cord partly within the casing, and extending to the exterior of the casing, a bell shaped socket member having 95 an outward flare and an opening for the cord within the casing, the cord being knotted with a knot within the socket and the cord passing through an opening within the socket and a helical spring seated within the 100 casing and extending around the socket and having its other end seated against the flaring flange of the socket.

In testimony that I claim the foregoing as my invention, I have signed my name 105 hereunder.

LOUIS W. GRANSNICK.
